UNITED STATES PATENT OFFICE

SALISBURY M. DAY, OF ROCHESTER, NEW YORK, ASSIGNOR TO GENERAL RAILWAY SIGNAL COMPANY, OF ROCHESTER, NEW YORK

RELAY

Application filed March 19, 1925. Serial No. 16,747.

This invention relates to track relays of the series type.

In railway signaling systems of the way-side type and in systems of automatic train control it is often found desirable to control a circuit when a train is near the exit end or some other point of a block. In railway signaling systems of the light signal type, a control of this kind is desirable in order to economize in the consumption of current used by such light signals in that these signals need not be illuminated until there is a train in the block approaching the signal. Also, in automatic train control systems it is often found necessary to transmit control influences to a passing train inductively by energy derived from a trackway source; and in order to economize in the use of this energy, it is found expedient to apply this energy only when there is a train present to which the influence is to be communicated. One way of manifesting the presence of a train at the approach to such signal, or a train control section, consists in the provision of a relay which is connected in series with the usual track battery between the battery and track and which is so adjusted that it assumes its energized position only when an approaching train draws an increased current from the track battery. It is, of course, understood that the normal track circuit current will vary over a wide range by reason of variation in ballast resistance and rail resistance, changes in voltage of the trackway source, and other variable factors, so that a relay connected in series with the trackway source requires very accurate adjustment in order that it will only respond to the presence of a train in the trackway and not to changes in current due to the variable local conditions just mentioned. Obviously, a relay of this type which is intended to respond to slight changes in current must be designed with a constant and the least possible friction between its relatively movable parts, and must be constructed so that its pick-up current (the current which will just raise the armature) and its drop-away current (the current which will just allow the armature to

drop when it is in its attracted position) may by suitable adjustment be readily changed to suit the particular track circuit in which the relay is to be used.

The present invention contemplates the provision of a relay for the purpose mentioned which affords the various adjustments in a very simple manner, which is constructed to withstand an appreciable amount of jar and vibration to which relays of this kind are subjected, in which the contact mechanism is readily accessible and is housed in a transparent cover so that inspection is readily made, and in which the adjustment of the relay and its pick-up and drop-away characteristics are directly indicated or at least may be ascertained from a direct indication.

Other objects, purposes and characteristic features of the invention will appear as the description progresses and will be apparent from the drawings forming a part of this application in which:

Fig. 1 shows a side elevation of one embodiment of the present invention in which the electro-magnet structure and the transparent casing thereof have been shown in sections;

Fig. 2 shows a front elevation of the relay shown in Fig. 1 with a portion of the transparent cover broken away;

Fig. 3 shows a top view of the relay, illustrating particularly the graduated core adjustment indicator; and

Fig. 4 illustrates a chart whereby the pick-up and drop-away characteristics of the relay may be determined if the core setting is known or vice versa.

Referring to the drawings the particular embodiment of the relay illustrated comprises a panel 1 of suitable insulating material such as porcelain, which has been shown secured to a suitable wall or support 2 by bolts 3. To the face of this insulating panel 1 is screw fastened a rectangularly shaped metal frame 4 having a rectangularly shaped groove in the bottom face thereof containing a gasket 5. Similarly, the insulating panel 1 is provided with a groove containing a gasket 6. The frame 4 contains a large circular

opening in which a cylinder 7 is secured by set screws 10. A gasket 11 is laid between the frame 4 and cylinder 7, as shown, so as to avoid the ingress of dirt and moisture into the contact mechanism chamber. This cylinder 7 has a cap 8 secured to its upper end by having the projecting flange 9 thereof rolled or spun over, so as to form a cup-shaped shell of magnetic material. A core 12 is provided having a screw driver slot so that it may be readily adjusted longitudinally within the shell 7—8, and is adapted to be locked in position by a lock nut 13.

Between the cap 8 and the lock nut 13 is contained a washer, dial or indicator 20 (see Figs. 1 and 3) having a lip 21 extending into the keyway 22 cut in the reduced threaded part of the core 12, so that this indicator turns as the core 12 is rotated for changing the adjustment of the core and in turn the air gap of the relay as more clearly pointed out hereinafter. This washer or indicator 20 has graduations marked thereon whereby the air gap is directly indicated for each adjustment thereof. In this connection it is desired to be pointed out at this time that commercial adjustments extend over substantially four complete revolutions of the indicator so that the scale reading itself is not enough but the number of threads extending above the lock nut must be taken into consideration in reading the air gap to which the relay is adjustable.

On the core 12 is slidably contained a coil 33 or winding 14 of the required number of turns to function in the average track circuit. This core is held in the extreme upper position by a coil spring 25 resting on a washer 26 held in place by a cotter-pin 27, 40 a suitable piece of insulating material or non-magnetic metal being contained between this spring and the coil.

Secured in and projecting from the lower end of the magnetic core 12 is a residual pin 30 of non-magnetic material. This residual pin is provided to limit the movement of a suitable armature 31 toward this core 12 when this core is adjusted to project beyond the lower edge of the shell 7—8, which 50 should however never occur in practice.

Non-magnetic guide means 31, attached to shell 7, project downwardly thereof to limit lateral movement of the armature 31.

In order to assure that the friction of the 55 movable armature 31 is not only substantially reduced to zero but does not vary under changes of temperature, or due to the collection of dirt, dust and the like, this armature, 31 is hingedly secured to a suitable 60 support. In the particular construction shown the armature 31 has riveted thereto a rather stiff member 32 which supports a contact finger 33 through the medium of an insulator 34, and also hingedly supports the 65 armature 31 by the provision of the thin

spring 35 riveted to this member 32 and secured to the shell 7 by screws 36 as shown, a small block of magnetic material being contained between the spring 35 and the shell 7, so that sufficient clearance between the movable portion of this spring and the shell 7 is afforded. The armature 31 is provided with a rivet 37 of non-magnetic material which is adapted to function as a residual stop so that the armature 31 can not get into physical contact with the magnetic shell 7.

On opposite sides and above and below respectively of the contact finger 33 are stationary contact arms 40 and 41 respectively. These contact arms 40 and 41 have their ends bent toward each other so as to be disposed above and below the multiple spring fingers 42 and 43 projecting from the contact finger 33. Divided or multiple spring fingers are used to afford a plurality of separate connections in multiple for each position of the relay. The ends of these stationary contact arms 40 and 41 are cross drilled and threaded and have stationary contacts 44 and 45 screw threaded therein and locked in position by suitable lock nuts. These adjustable stationary contacts 45 and 44 each includes a head of rollable metal such as brass which is hollowed out and contains a contact block 46 of suitable refractory material such as carbon or carbon impregnated with suitable metal. In the manufacture of these contacts several layers of tin foil are laid in the cavity of the metallic portion upon which the 100 around carbon blocks are placed after which the top edges of the metal are spun firmly around these carbon blocks or buttons. This tin foil produces a cushioning effect and reduces the contact resistance between the 105 metal and the carbon. Directly below the contact arm 33 a stud or bolt 47 projects through the panel 1 which is connected to this contact arm 33 by a flexible connection or pig-tail 48. The stationary contact arms 110 40 and 41 and the stud 47 are connected to binding posts 50, 51 and 52 respectively as shown. A spring clip or fastener 53 is supported by the binding post 52 and is adapted to support a transparent cover 54 which engages the gaskets 5 and 6 respectively and is held against the gasket 6 by a knurl headed screw 55 engaging the frame, this screw being held against removal by a seal 57 of the usual construction. At the top of the insulating panel 1 are provided similar binding posts 58 and 59 to which the leads of the coil 14 are connected.

By referring to the drawings and more particularly to Fig. 1, it will readily appear, 125 with the relay winding 14 energized by a certain current, which may be assumed to be the current flowing in the track circuit under most favorable circumstances while the track circuit is unoccupied, that the re- 130

lay may be adjusted to just drop its armature for this current value for a particular adjustment of the core 12 existing at this time. In practice this relay in accordance with the present invention is adjusted in the factory as far as certain fixed adjustments are concerned, and after these adjustments have been made the glass cover 54 is put in place and sealed up, so that employees of the railway company purchasing such relay cannot tamper with these fixed adjustments.

In making these fixed adjustments the relay is first energized after which contact 44 is adjusted to a position to give a predetermined contact pressure. This contact pressure is determined by the wipe the contact 42 makes over the surface of the carbon button 46 as the relay is moved from its de-energized position to its energized position and vice versa. After this adjustment has been made, the back contact 45 is adjusted so as to be spaced from the contact 43 a certain distance sufficient to assure breaking of the circuit at both the front and back contact when the relay is operated to break such circuit. After these adjustments have been made, and the contacts 44 and 45 have been locked in position, the core 12 is adjusted to a position where the residual pin 30 just touches the armature 31. With the core 12 and the indicator 20 in this position the top of the cap 8 has a zero mark or starting mark 23 chiseled thereon adjacent the zero on the indicator or dial 20.

When the relay is shipped to the customer a calibration chart such as shown in Fig. 4 is sent with each relay. Along the horizontal axis of this chart are plotted the number of turns T , the graduations signified by the number of threads projecting above the lock nut 13 and the graduation on the dial 20 adjacent the zero mark 23, and the air gap in decimals of an inch; whereas amperes of relay current are plotted along the vertical axis of the chart. On this chart are plotted two curves, one of which designates the pick-up current or the current required to pick up the relay for each core setting; whereas the other current indicates the drop-away current or current which will just drop the relay for each core setting.

As previously explained, the relay of this invention is intended to be used with the ordinary and well known normally closed track circuits of block signaling systems, usually in series with the track battery or other source and between the source and the track, so that its armature is normally retracted when there is no train present on the track circuit, and is attracted to close the contact of the relay when a train enters the track circuit. Considering this application of the relay, it will be evident that the energizing current passing through the winding

of the relay corresponds to the total current supplied to the track circuit from the track battery. In practice, this energizing current will vary considerably in different length blocks, and in the same block, due to changes in ballast resistance. In order that the relay may operate properly when applied to track circuits of different length, and also under different ballast conditions, that is, may maintain its armature in the retracted position when no trains are present and attract the armature when a train enters the track circuit, it is found in practice that both the pick-up and the drop-away current must, generally speaking, be changed to adapt the relay for the different situations, and it has been demonstrated that such simultaneous change in both the pick-up and drop-away current is ordinarily obtained by the single adjustment of the core position in the relay constructed according to the present invention, this not being true of other tractive relays in which the two air gaps in series in the magnetic circuit are simultaneously changed by the adjustments.

With a relay constructed in accordance with the present invention together with a calibration curve such as shown in Fig. 4 it is a comparatively simple task for the signal maintainer to properly adjust the relay, especially when used as a series relay connected in series with the usual track battery of a track circuit. Referring to the curves given in Fig. 4 which represent actual values of current and core adjustments for one particular design of relay embodying the present invention, let us assume that by inserting an ammeter in series with the relay it is found that the current upon entrance of a train upon the track circuit from the other or track relay end is 1 ampere, and that the current is 0.6 ampere when the block is unoccupied. By looking at the chart it readily appears that the core adjustment for these current values should be such as to correspond to 30 graduations, or one and one half turn of the indicator dial 20 to the left of its zero position, thus giving an air gap of 0.07 inches. In the same way adjustment may be made for other current values when the block is unoccupied and entered respectively.

On certain railways where ballast conditions are poor, that is, where the leakage of current from one rail to the other is very high in wet weather but much lower in dry weather, it is found necessary to adjust advance lighting or series relays of this and other types differently for different seasons of the year, and if a relay embodying the present invention is used a record of the adjustment of the seasons of the previous year may be kept and the same adjustments made for the same seasons of the present and following years. Further, if desired, the adjustments for the

different seasons of the year may be marked directly on the chart for the particular relay, for instance, vertical lines might be drawn at the particular core settings found proper, together with the period of the year during which the relay should be adjusted to such core settings written on such line. The net result is, the relay embodying the present invention together with its calibration chart at a glance tells just what the characteristics of the relay are and what other characteristic may be obtained by adjustment.

In addition to the marked superiority and advantages of the particular construction of a relay according to this invention, for its application to track circuits in railway signaling, this relay has a more efficient magnetic circuit and less magnetic leakage than the types of tractive relays commonly used.

A relay particularly adaptable for use as a series relay in track circuits for railway signaling purposes has thus been provided in which the armature is hingedly or yieldably supported as distinguished from pivotally supported so that its friction is reduced to a minimum and does not vary with changes of temperature, extent of use, collection of dirt or the like; and which is constructed to afford the necessary changes in its operating characteristics so that it will assume its energized or de-energized position respectively over a large range of minimum and maximum values of current between which values it is to function, this being obtained by adjusting the core vertically in the coil in a manner so that the position of the core is indicated and the position of the coil remains definite, firmly holding the coil against a retaining surface, so that jars and vibration will not disturb or change the same. Also, the contact mechanism of this relay is housed in a moisture and air-tight chamber, so as to keep out the moisture and corrosive gases usually present along railway tracks, which gases and moisture might corrode this mechanism, which housing is of a shape to engage both the panel on which the relay is mounted and also the frame structure for supporting the electro-magnet thereof.

Having thus shown and described one specific embodiment of the present invention and having pointed out certain features of the invention rather specifically it is desired to be understood that this has been done for the purpose of clearly disclosing the invention rather than pointing out the scope thereof, and that various changes and modifications may be made to adapt the invention to other circuits of various kinds without departing from the scope of the invention or the idea of means underlying the same.

What it is desired to be secured by Letters Patent is:—

1. An approach light signal relay for connection to the track in series with a track circuit battery bridged directly across the rails of a railway track comprising, a shell of magnetic material, a magnetizable core threaded into said shell so as to be vertically adjustable therein, a hinged armature adapted to move toward and away from said core and shell, a coil on said core which when energized causes said armature to be attracted toward said core and shell, and a coil spring surrounding said core for holding said coil against said shell. 70

2. An approach light signal relay for connection in series to the track with a track circuit battery bridged directly across the rails of a railway track comprising, a support, a cylindrical core carried by, and adjustable vertically along, the axis of said support, an armature hinged so as to be movable toward and away from said core, a coil slidably mounted on said core, a spring for maintaining said coil against said support and a contact operated by movement of said armature. 85

3. In an approach signal relay for railway signaling purposes, to be connected between the track and the track battery, the combination of an armature hingedly supported by a leaf-spring, a contact arm supported by said armature and having projecting spring contact fingers, adjustable stationary front and back contacts adapted to cooperate with said fingers, a core of magnetic material adjacent the armature, 95 a winding slidably received by the core, the core being adjustable to vary its air gap and a winding supported on the core above said armature, whereby the operating characteristics of said relay can be changed by adjusting said core. 100

4. An approach signal relay for railway signaling purposed to be connected in series with the track battery to the track comprising, a shell of magnetic material of general inverted cup-shape having a core arranged coaxially and adjustable longitudinally therein, an armature hingedly but non-pivotally fastened to one side of said shell so as to provide a flux path from said core 110 to said shell, a coil surrounding said core within said shell and means to hold the coil fixed in relation to the shell.

5. A relay for use with approach signals for railway signaling purposes, comprising, a shell of magnetic material of general inverted cup-shape having a core arranged coaxially therein which is adjustable longitudinally, an armature hingedly but non-pivotally fastened to one side of said shell so as to provide a flux path from said core to said shell, non-magnetic stop means associated with the armature and shell for limiting the movement of said armature toward 125 130

said shell, and a coil surrounding said core within said shell.

6. An approach signal relay for railway signalling purposes, comprising, a shell of magnetic material of general inverted cup-shape having a core arranged coaxially and adjustable longitudinally therein, an armature hingedly but non-pivottally fastened to one side of said shell so as to provide a flux path from said core to said shell, non-magnetic stop means for limiting the movement of said armature toward said shell, a second non-magnetic stop means for limiting the movement of said armature toward said core, and a coil surrounding said core within said shell.

7. A relay for railway signaling purposes comprising, a shell of magnetic material of general inverted cup-shape having a core arranged coaxially therein which is adjustable longitudinally, an armature hingedly but non-pivottally fastened to one side of said shell so as to provide a flux path from said core to said shell, non-magnetic stop means for limiting the movement of said armature toward said shell, non-magnetic stop means for limiting the movement of said armature toward said core, a coil surrounding said core within said shell, and a spring supported by said core for holding said coil fixed relative to said shell regardless of the adjusted position of said core.

8. An approach signal relay for use in series with a track battery to the track, comprising a panel, a shell type electro-magnet including a core and a shell supported on said panel, an armature hinged to said shell at a point adjacent said panel, a contact finger supported by said armature and projecting away from said panel, two stationary contact arms, fixed to and projecting outwardly from said panel above on one side and below on the other side of said contact finger respectively, and stationary contacts adjustably secured to said contact arms adapted to be engaged by said contact finger when said armature is in its attracted and retracted position respectively.

9. A relay comprising a panel, a shell type electro-magnet including a core and a shell supported on said panel, an armature hinged to said magnet at a point adjacent said panel, a contact finger supported by said armature and projecting away from said panel, two stationary contact arms projecting outwardly from said panel one on one side and above, and one on the other side and below, said contact finger respectively, stationary contacts adjustably secured to said contact arms adapted to be engaged by said contact finger when said armature is in its energized and de-energized position respectively, and non-magnetic guide means secured to said magnet on opposite sides of said armature

for limiting the lateral movement of said armature.

10. An approach signal relay for use in series to the track with a track battery, comprising a panel, a shell type electro-magnet including a core and a support on said panel, an armature hinged to said magnet at a point adjacent said panel, a contact finger supported by said armature and projecting away from said panel, two stationary contact arms projecting outwardly from said panel above on one side and below on the other side of said contact finger respectively, and stationary contacts adjustably secured to said contact arms and adapted to be engaged by said contact finger when said armature is in its attracted and retracted position respectively, the core of said magnet being adjustable longitudinally, whereby the drop-away current of the relay may be adjusted by adjusting the core longitudinally and the pick-up current may be adjusted by adjusting the position of the stationary contact below said contact finger.

11. An approach signal relay of the type described, comprising the combination of a shell, a core adjustably supported in said shell, a winding on said core, an armature adapted to bridge the ends of said core and shell, and micrometric indicating means for indicating the air gap between said core and armature when said armature is in its attracted position against said shell.

In testimony whereof I affix my signature.
